RAILWAY AND TRAMWAY RAIL AND WHEEL
FLANGE LUBRICATIONEdwin George Butcher, Wahroonga, and William
Edmund Jupe, Eastwood, New South Wales,
AustraliaApplication August 19, 1933, Serial No. 685,942

17 Claims. (Cl. 184—3)

This invention relates to improved means for intermittently supplying very small quantities of lubricant of high viscosity to the wheel flange side of the head of a railway or tramway rail 5 and indirectly to the inner and upper portion of each wheel flange at or near curves on the track without making any structural alterations to the rail or to the track.

A lubricant container, fitted with a delivery 10 mouth which is positioned near the wheel flange side of the rail head and is provided with a weighted plunger, is secured to the rail so that vibration of the rail due to oncoming wheels effects vibration of the container with the result 15 that the plunger during the period of vibration forces further quantities of lubricant from the container to the delivery mouth.

To regulate the distribution and the amount 20 of lubricant delivered by the delivery mouth of the container, a laterally movable metal tongue, mounted as a gate over the delivery mouth and in the line of travel of the flanges of the oncoming wheels, is adapted, when moved by a wheel flange, to squeeze upwards and to direct 25 to the wheel flange side of the rail head a small quantity of lubricant from the mouth of the container.

In the accompanying drawing which illustrates 30 one form of the invention:—

30 Fig. 1 is a part sectional elevation of a lubricator fitted to a rail;

Fig. 2 is a plan of the same showing portion 35 of the rail;

Fig. 3 is a central sectional elevation of the 40 same;

Fig. 4 is a plan of a laterally movable tongue;

Fig. 5 is an end elevation of the tongue;

Fig. 6 is a sectional elevation of the tongue.

A container 10, filled with stiff lubricant such 45 as lubricating grease, is fitted near its base with a gradually shallowing spout 11 also filled with the lubricant and extending towards the rail. The delivery mouth of the container is a narrow slot 12 formed near the top of the side of the spout remote from the rail 13 and extends 50 along the width of the spout parallel to the rail. An adjustably weighted plunger 14 rests on the lubricant within the container 10.

The container 10 is resiliently mounted near 55 the track on springs 15 which are adjustably secured to approximately horizontal bars 16 as by means of elongated slots and bolts 17. The bars 16 pass under the rail and are secured thereto by lugs 18 and 19. By adjustment of the bolts 17 and the insertion of spacers between the

springs and the bars the head of the spout 11 is forced against the under face of the rail head and the mouth 12 positioned so that it lies approximately in the plane of the wheel flange face 20 of the rail head.

Vibration of the rail 13 by the oncoming 5 wheels effects vibration of the container 10 with the result that the plunger 14 forces lubricant from the container to the mouth 12.

To control the amount and the direction of 10 application of lubricant from the mouth 12 the lower lip of the mouth is fitted with a pocket 21 which is of approximately V shape and is adapted to house the bent lower end of a resilient metal tongue 22. The upper end of the 15 tongue passes over the mouth 12 and extends upwards to about midway of the face 20 of the rail head thus forming a gate for the mouth. The outer face of the tongue is fitted with or 20 formed as a wheel flange contacting member 23 which, in the form illustrated, is of triangular vertical section which decreases in width of base from the centre to each of the lateral ends of the tongue. The upper end of the tongue is, preferably, cambered away from the rail 25 head and each of its lateral ends is formed as a spreading plate 24 which normally rests against the rail face 20 and is adapted to be forced against this face by each wheel flange to prevent 30 escape of lubricant. A side plate 25 on each lateral end of the tongue nests under the rail head and prevents excessive upward movement 35 of the tongue.

Set screws 26 mounted in the outer wall of 40 the pocket 21 bear against the face of the tongue 35 and are adapted to regulate the extent of lateral movement of the tongue thus controlling the amount of lubricant distributed from the mouth 12 on the passage of each wheel flange. The set screws may be locked after they have been 45 adjusted.

Vertical webs 27 serve to stiffen the pocket 21.

In operation, the mouth 12 having been positioned approximately in the vertical plane of the face 20 of the rail head, vibration of the 45 rail 13 due to oncoming wheels is transmitted through the bars 16 to the container 10 so that the plunger during the period of the vibration forces lubricant to the mouth 12. Much of this vibration is upward, so that there is upward 50 effort against the inertia of the plunger, with the result that lubricant is forced from the mouth both before and at the instant of arrival at the device of the oncoming wheels; this action occurs even when the container is 55

mounted directly upon the bars 16, even with lubricant of relatively high viscosity; and, when the container is spring mounted as shown, it has been found that there is more vertical effort of the content of the container against the plunger. When a wheel flange bears against the ramp face of the tongue 22 the head of the tongue is moved towards the rail head to close the mouth 12. Portion of the lubricant in the mouth is thereby squeezed upwards and directed to the face 20 of the rail head and the inner upper portion of the wheel flange is at the same time lubricated. When the wheel passes over the ramp the resilience of the tongue automatically returns the tongue to its original position in readiness for the next wheel flange.

We claim:—

1. A rail and wheel flange lubricator adapted to supply lubricant intermittently in small quantities to the wheel flange side of a rail head and comprising a lubricant container filled with lubricant and positioned near the track, a container delivery mouth positioned near and parallel to the wheel flange side of the rail head, a weighted plunger within the container resting on the lubricant, springs secured to the base of the container, and horizontal bars carrying the springs and secured to the rail.

2. A rail and wheel flange lubricator adapted to supply intermittently small quantities of lubricant to the wheel flange side of a rail head and comprising a lubricant container filled with lubricant and positioned near the track, a container spout projecting from the container towards the rail and adapted to be forced under and in contact with the under face of the rail head, a narrow delivery mouth of the container positioned near and parallel to the wheel flange side of the rail head, a weighted plunger resting on the lubricant within the container, horizontal bars secured to the rail foot, and springs supporting the container and adjustably secured to the bars.

3. A rail and wheel flange lubricator adapted to supply lubricant to the wheel flange side of the rail head and comprising a lubricant container filled with lubricant and positioned near the track, an open delivery mouth of the container positioned near and parallel to the wheel flange side of the rail head, a weighted plunger resting on the lubricant within the container, horizontal bars securing the container to the rail foot, and a resilient metal tongue detachably mounted on a lip of the delivery mouth and adapted to be moved towards and away from the mouth.

4. A rail and wheel flange lubricator adapted to supply intermittently small quantities of lubricant to the wheel flange side of a rail head and comprising a lubricant container filled with lubricant and positioned near the track, an open delivery mouth of the container positioned near and parallel to the wheel flange side of the rail head, a weighted plunger resting on the lubricant within the container, horizontal bars supporting the container and secured to the rail foot, a laterally movable metal tongue mounted on a lip of the delivery mouth of the container, and a screw arranged to adjust the position of said tongue with respect to said mouth.

5. A rail and wheel flange lubricator adapted to supply intermittently small quantities of lubricant of high viscosity to the wheel flange side of the rail head and comprising a lubricant container filled with lubricant and positioned

near the track, a weighted plunger resting on the lubricant within the container, horizontal bars supporting the container and secured to the rail foot, an open delivery mouth of the container positioned near and parallel to the wheel flange side of the rail head, a laterally movable metal tongue carried by a lip of the delivery mouth and projecting over and above the mouth, and a wheel flange contacting member on the outer face of the tongue.

6. A rail and wheel flange lubricator adapted to supply intermittently small quantities of lubricant to the wheel flange side of a rail head and comprising a lubricant container filled with lubricant and positioned near the track, a weighted plunger resting on the lubricant within the container, springs supporting the container, horizontal bars secured to the springs and secured to the rail foot, a delivery mouth of the container positioned near and parallel to the wheel flange side of the rail head, a laterally movable resilient metal tongue detachably mounted on a lip of the delivery mouth, a wheel flange contacting member on the outer face of the tongue, and a ramp face on the contacting member.

7. A rail and wheel flange lubricator adapted to supply intermittently small quantities of lubricant to the wheel flange side of a rail head and comprising a lubricant container positioned near the track and filled with lubricant, a weighted plunger resting on the lubricant within the container, springs supporting the container, horizontal bars carrying the springs and secured to the rail foot, a delivery mouth of the container in the form of a slot positioned near the wheel flange side of the rail head, a laterally movable metal tongue mounted on a lip of the delivery mouth, a screw arranged to adjust the position of said tongue with respect to said mouth, side plates on the tongue projecting under the rail head, and a ramp on the outer face of the tongue in the line of travel of the wheel flanges.

8. A rail and wheel flange lubricator adapted to supply intermittently small quantities of lubricant to the wheel flange side of a rail head and comprising a lubricant container filled with lubricant and positioned near the track, a weighted plunger resting on the lubricant within the container, springs supporting the container, horizontal bars carrying the springs and secured to the rail foot, a delivery mouth of the container positioned near and parallel to the wheel flange side of the rail head, a pocket on a lip of the mouth, a laterally movable resilient metal tongue housed in the pocket and extending over and above the mouth, a spreading plate at each lateral end of the tongue, a side plate on each lateral end of the tongue and projecting under the rail head, a wheel flange contacting member on the upper end of the tongue, a ramp face on the contacting member, and set screws on the pocket adapted to regulate the extent of lateral movement of the tongue.

9. A lubricator comprising a lubricant-container having a delivery-mouth adapted to be positioned adjacent to a side of a rail-head, a weighted plunger adapted to rest on lubricant in said container, a supporting spring on said container, and a supporting member adapted to be connected to said spring and rigidly to a rail.

10. A lubricator comprising a lubricant-container, a spout extending from the bottom of said container and having in its outer portion

- opposite walls one of which is formed to abut the under side of a rail-head and the terminal edges of said walls affording a delivery-mouth, a weighted plunger adapted to rest on lubricant in 5 said container, and a supporting member for said container connectible thereto and rigidly connectible with a rail whereby wheel-imparted vibration is imparted upwardly to said container and lubricant therein against the inertia 10 of said plunger whereby lubricant is forced from said mouth.
11. A lubricator comprising a lubricant-container having a delivery-mouth adapted to be positioned adjacent to a side of a rail-head, a 15 yieldable tongue extending across said mouth and adapted to be pressed toward said mouth by a wheel flange, a weighted plunger adapted to rest on lubricant in said container, and a supporting member for said container connectible 20 thereto and rigidly connectible to a rail whereby wheel-imparted rail vibration is imparted to said container and said plunger thereby caused to force lubricant from said mouth.
12. A lubricator comprising a lubricant-container having a delivery-mouth adapted to be positioned adjacent to a side of a rail-head, a delivery-restricting yieldable tongue extending across said mouth and adapted to be pressed toward said mouth by a wheel-flange, means for 25 adjusting the position of said tongue with respect to said mouth, a weighted plunger adapted to rest on lubricant in said container, and a mounting member for said container connectible thereto and rigidly connectible to a rail 30 whereby wheel-imparted rail vibration is imparted to said container and said plunger thereby caused to force lubricant from said mouth.
13. A lubricator for intermittent supply of lubricant to the side of a rail-head comprising 35 a container of lubricant positioned near the rail track, a spout extending from the base of the container adapted to be positioned adjacent to the under face of the rail-head, a delivery-mouth of the spout positioned near and substantially parallel to the wheel-flange side of the rail-head, a weighted plunger resting on lubricant in the container, springs supporting the container, and bars carrying the springs and secured to the rail.
14. A lubricator comprising a container of lubricant having a delivery-mouth adapted to be positioned adjacent to a side of a rail-head, a weighted plunger resting on and supported by lubricant in the container, and a mounting member for said container connectible thereto and rigidly connectible to a rail whereby wheel-imparted rail vibration is imparted upwardly to said container and lubricant therein against the inertia of said plunger whereby lubricant is 10 forced from said mouth.
15. A lubricator comprising a container of lubricant, a spout extending from the bottom of said container and terminating in a mouth adapted to be positioned adjacent to a side of a rail-head, a weighted plunger resting on and supported by lubricant in the container, and a supporting member for said container connectible thereto and rigidly connectible to a rail whereby wheel-imparted rail vibration is im- 15 parted upwardly to said container and lubricant therein against the inertia of said plunger whereby lubricant is forced from said mouth.
16. The combination, with a track-rail, of a container of lubricant having a delivery-mouth 20 positioned adjacent to the side of the head of the rail, a weighted plunger resting on and supported by lubricant in the container, and a member rigidly connected to and extending laterally from the rail and connected with said 25 container whereby wheel-imparted rail vibration is imparted upwardly to said container and lubricant therein against the inertia of said plunger whereby lubricant is forced from said 30 mouth.
17. The combination, with a track-rail, of a container of lubricant, a spout extending from the bottom of said container and terminating in a mouth at the side of the head of the rail, a weighted plunger resting on and supported by 35 lubricant in the container, and a member rigidly connected to and extending laterally from the rail and connected with said container whereby wheel-imparted rail vibration is imparted upwardly to said container and lubricant therein 40 against the inertia of said plunger whereby lubricant is forced from said mouth.

EDWIN GEORGE BUTCHER.
